Primary Examiner — Sheryl Lane*Assistant Examiner* — Leisha N Price(57) **CLAIM**

The ornamental design for a screw, as shown and described.

DESCRIPTION

FIG. 1 is a perspective view of a screw showing my new design;

FIG. 2 is another perspective view thereof;

FIG. 3 is a left side view thereof with the right side view being a mirror image of;

FIG. 4 is a front view thereof with the rear view being a mirror image of;

FIG. 5 is a top plan view thereof; and,

FIG. 6 is a bottom plan view thereof.
